UNITED STATES PATENT OFFICE

153,321

DESIGN FOR A DISPLAY CASE

Paul M. Ressinger, Chicago, Ill.

Application July 25, 1947, Serial No. 140,511

Term of patent 7 years

(Cl. D80—11)

To all whom it may concern:

Be it known that I, Paul M. Ressinger, a citizen of the United States, residing at Chicago, in the county of Cook and State of Illinois, have invented a new, original, and ornamental Design for a Display Case, of which the following is a specification, reference being had to the accompanying drawing, forming part thereof.

The figure is a perspective view of a display case, showing my new design, the back of the display case being plain.

I claim:

The ornamental design for a display case, as shown and described.

PAUL M. RESSINGER.
